UNITED STATES PATENT OFFICE

WILLIAM J. CASEY, OF CHICAGO, ILLINOIS, ASSIGNOR TO COLUMBIA METAL PRODUCTS COMPANY, OF CHICAGO, ILLINOIS, A CORPORATION OF ILLINOIS

BEATER

Application filed June 14, 1926. Serial No. 115,824.

This invention has to do with culinary beaters of the type commonly used for whipping cream, beating eggs and mixing the ingredients in salad dressings, custards, light batters and similar liquids.

The beaters which heretofore have been most extensively used for the purposes described have been characterized by an upright shaft, a blade secured to the shaft near the lower end thereof for insertion within a liquid receptacle, and an operation mechanism connected with the shaft near the upper end thereof for rotating the blade.

In the operation of such beaters, however, the upper and lower ends of the rotating shaft have assumed the end thrust necessarily transmitted through the beater in operating the same against the bottom of a receptacle, with the result that a considerable amount of the force required to rotate the blade has been wasted in friction at those points, and a specially designed receptacle having a centering indentation has been required.

The object of the present invention is to provide an improved beater of the type described, which is light, strong and durable in construction, is inexpensive to manufacture, will operate easily in any kind of receptacle with practically no friction, and may be readily taken apart, either for cleaning or for substitution of differently shaped but interchangeable blades.

Other objects and advantages of the invention will be evident to those skilled in the art upon a full understanding of the construction, arrangement and operation of the improved beater.

One embodiment of the invention is herein presented for the purpose of exemplification, but it will of course be understood that the invention is susceptible of embodiment in other modified forms coming equally within the comprehensive scope of the appended claims.

45 In the accompany drawing:

Fig. 1 is a side view of a beater constructed in accordance with the invention; and

Fig. 2 is a different side view of the same, showing certain portions thereof in section.

50 It will be observed in the drawing that the

frame of the beater is a sheet metal strip 10 which is provided at its upper end with a handle 11. A gear 12 is journalled on a pin 13 which projects laterally from the strip 10 intermediate the ends thereof, and a crank handle 14 is secured to the gear for rotating the same. A long rod 15 is detachably secured at its upper end to the strip 10, by passing through an aperture in a laterally bent portion 16 of the strip and screwing into an aperture in another laterally bent portion 17, and is provided at its lower end with an enlarged head 18 which is peripherally knurled to facilitate screwing of the upper end of the rod 15 into or out of the aperture in the portion 17. A long tubular shaft 19 is journalled about the rod 15 between the laterally bent portion 16 of the strip and the enlarged head 18 on the rod. A pinion 20 is secured to the upper end of the shaft 19 in mesh with the gear 12, and a beating element in the form of a curved perforate blade 21 is secured to the lower end of the shaft.

In operation, the beater is held in an upright position, with the blade 21 within the receptacle containing the liquid to be beaten, and with the head 18 against the bottom of the receptacle. The beater is held firmly in that position by means of the handle 11, and the crank handle 14 is turned, resulting in a rapid rotation of the blade 21. The head 18 on the lower end of the rod 15 does not rotate with the blade but is held stationary against the bottom of the receptacle, and all end thrust in the beater is assumed by the head, permitting the blade and its associated moving parts to rotate with perfect freedom. In order to take the beater apart, for the purpose of either cleaning or changing the blade, it is only necessary to unscrew the rod 15 a few turns, whereupon the same may be withdrawn, and the shaft 16, with its pinion and blade, removed.

I claim:

1. In a beater of the type described, a frame, a handle secured to the frame for holding the same stationary, a gear journalled on the frame, a crank handle secured to the gear for rotating the same, an extension of the frame, a tubular shaft journalled about the

- extension, a pinion secured to the shaft near one end thereof in mesh with the gear, a beating element secured to the shaft near the other end thereof, and an enlargement on the 5 end of the extension for preventing the shaft journalled on the extension from shifting axially, said enlargement being removable from the frame, a tubular shaft journalled about the shaft and beating element.
- 10 2. In a beater of the type described, a frame, a handle secured to the frame for holding the same stationary, a gear journalled on the frame, a crank handle secured to the gear for rotating the same, an extension of 15 the frame a tubular shaft journalled about the extension, a pinion secured to the shaft near one end thereof in mesh with the gear, a beating element secured to the shaft near the other end thereof, and an enlargement on 20 the end of the extension for preventing the shaft journalled on the extension from shifting axially, said enlargement being removable from the frame together with the extension whereby to permit removal of the shaft 25 and beating element.
3. In a beater of the type described, a frame, a handle secured to the frame for holding the same stationary, a gear journalled on the frame, a crank handle secured to 30 the gear for rotating the same, a rod detachably secured to the frame, a tubular shaft journalled on the rod, a pinion secured to the shaft near one end thereof in mesh with the gear, a beating element secured to the shaft 35 near the other end thereof, and an enlargement fixedly associated with the rod beyond the shaft for preventing axial movement of the shaft and for use as a handle in effecting detachment of the rod.
- 40 4. In a beater of the type described, a frame, a handle secured to the frame for holding the same stationary, a gear journalled on the frame, a crank handle secured to the gear for rotating the same, a rod detachably secured to the frame, a tubular shaft journalled 45 on the rod, a pinion fixedly secured to the shaft near one end thereof in mesh with the gear, a beating element fixedly secured to the shaft near the other end thereof, and an enlarged head fixedly secured to the rod beyond 50 the end of the shaft for engagement with the bottom of the receptacle in which the beater is used and for use as a handle in effecting detachment of the rod.
- 55 5. In a beater of the type described, a frame, a handle secured to the frame for holding the same stationary, a gear journalled on the frame, a crank handle secured to the gear for rotating the same, a rod screwed 55 into the frame, a tubular shaft journalled on the rod, a pinion secured to the shaft near one end thereof in mesh with the gear, and a beating element secured to the shaft near the other end thereof, said rod extending beyond the end of the shaft and being provided

with an enlarged head for engagement with the bottom of the receptacle in which the beater is used and for use as a handle in screwing the rod.

6. In a beater of the type described, a frame, a handle secured to the frame for holding the same stationary, a gear journalled on the frame, a crank handle secured to the gear for rotating the same, a rod detachably secured to the frame, a tubular shaft journalled about the rod between end abutments on the frame and the rod, a pinion secured to the shaft near one end thereof in mesh with the gear, and a curved perforate blade secured to the shaft near the other end thereof, said rod being in screw-threaded engagement at its upper end with the frame end being provided at its lower end with an enlarged head both for engagement with the bottom of the receptacle in which the beater is used and for screwing the rod into or out of engagement with the frame whereby to permit removal of the pinion, shaft and blade as a unit upon removal of the rod.

7. In a beater of the type described, a frame, a handle secured to the frame for holding the same stationary, a gear journalled on the frame, a crank handle secured to the gear for rotating the same, a rod detachably secured to the frame, a tubular shaft journalled about the rod, an abutment on the frame for preventing axial movement of the shaft in one direction, an abutment on the rod for preventing axial movement of the shaft in the opposite direction, a pinion secured to the shaft near one end thereof in mesh with the gear, and a blade secured to the shaft near the other end thereof, said rod being in screw-threaded engagement at its upper end with the frame and being provided at its lower end with means for screwing the rod into or out of engagement with the frame whereby to separate said abutments and permit removal of the pinion, shaft and blade as a unit upon removal of the rod.

In testimony whereof I have hereunto subscribed my name.

WILLIAM J. CASEY.

CERTIFICATE OF CORRECTION.

Patent No. 1,744,445.

Granted January 21, 1930, to

WILLIAM J. CASEY.

It is hereby certified that error appears in the printed specification of the above numbered patent requiring correction as follows: Page 2, line 8, claim 1, strike out the comma and words ", a tubular shaft journaled about" and insert instead "whereby to permit removal of", and in line 82, claim 6, for the word "end" second occurrence read "and"; and that the said Letters Patent should be read with these corrections therein that the same may conform to the record of the case in the Patent Office.

Signed and sealed this 4th day of March, A. D. 1930.
